(57) CLAIM

The ornamental design for a vehicular front light bar, as shown and described.

DESCRIPTION

FIG. 1 is a front perspective view of the vehicular front light bar of the present invention showing my new design;
FIG. 2 is a top elevational view thereof;
FIG. 3 is a front elevational view thereof;
FIG. 4 is a bottom plan view thereof;
FIG. 5 is a left side view thereof;
FIG. 6 is a right side view thereof;
FIG. 7 is a rear elevational view thereof;
FIG. 8 is a front perspective view of a second embodiment of the vehicular front light bar of the present invention showing my new design;
FIG. 9 is a top plan view thereof;
FIG. 10 is a front elevational view thereof;
FIG. 11 is a bottom plan view thereof;
FIG. 12 is a left side view thereof;
FIG. 13 is a right side view thereof; and,
FIG. 14 is a rear elevational view thereof.

The dotted lines depicted in the drawings form no part of the claimed design.
